HEINRICH ZOELLY, OF ZURICH, SWITZERLAND.

EXPLOSION GAS-TURBINE.

1,089,892.

Specification of Letters Patent. Patented Mar. 10, 1914.

Application filed January 6, 1913. Serial No. 740,470.

To all whom it may concern:

Be it known that I, HEINRICH ZOELLY, a citizen of the Republic of Switzerland, residing at Zurich, Switzerland, have invented new and useful Improvements in Explosion Gas-Turbines with at Least One Piston-Compressor; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

The invention relates to an explosion gas turbine, which is provided with at least one piston compressor. The hitherto known turbines of this type possess the draw-back that the pressure existing in the explosion chamber and therefore the discharge velocity of the combustion gases through the nozzles is very variable since the peripheral speed of the moving blades can only correspond with a single value of the discharge velocity, all other values of the speed were either too high or too low, and therefore the so called hydraulic efficiency and therewith the total efficiency of the turbine was insufficient.

The purpose of the present invention is to do away with this drawback.

The invention consists in applying special devices and means for rendering the pressure in the explosion chamber as constant as possible. For this purpose the combustion gases act after their ignition, that is to say in the moment in which they tend to assume a large volume and a large pressure, in the first instance on the working piston of a two-cycle engine, one end of the cylinder of which is continually in good open connection with the explosion chamber. At the beginning of the explosion the working piston rapidly recedes and transmits the work received from the combustion gases for compressing the combustion air and fuel to an auxiliary medium and partly also to the reciprocating masses. At the return stroke of the working piston the masses of the piston and the medium deliver the greater part of the previously received work again to the gases left in the combustion chamber, so

that the gases flow through the nozzles at an utmost constant pressure and in consequence thereof at an utmost constant speed. In the accompanying drawings the invention is illustrated by a c example.

In the form of construction shown in Figure 1 a single cylinder engine, and in the form of construction shown in Fig. 2, a twin-cylinder engine is connected to the combustion chamber.

In Fig. 1, *a* designates the working piston and *b* the compressor piston rigidly coupled thereto. The medium for driving the gas turbine flows into the working or combustion cylinder *c* at the left side of the piston *a*. The space at the right side of the piston *a* is connected by a pipe *d* with a large receptacle *e* in which an almost constant pressure p_0 is maintained. The compressor cylinder may be always open to the left. Its right side is temporarily connected by a pipe *g* to an air receptacle *h*, from which the air necessary for combustion flows at the proper moment through the pipe *i* into the combustion chamber *k*. A special pump *z* supplies the combustion chamber *k* with fuel through the pipe *l*. When the working piston is in its extreme position to the left or moves from the right toward this position, the ignition is performed in the chamber *k* in a wellknown manner by a special device, the combustion mixture tends to rapidly expand and moves the working piston *a* first at a high speed toward the right. Mainly two forces counteract this movement, first the pressure p_0 existing in the receptacle *e*, which is transmitted by the pipe *d* to the right side of the piston *a*, second the pressure of the air existing at the right side of the compressor piston *b*, which pressure at first is not larger than the atmospheric pressure. Besides there counteracts the friction of the piston rod and pistons and the inertia of the same and of the auxiliary medium. The working piston *a* and the compressor piston *b* are suddenly moved toward the right, so that the air at the right side of the compressor piston is compressed until the valve *m* in the pipe *g* is opened and the compressed air is discharged through the pipe *g* into the compressed air receiver *h*. From this moment until the end of the piston stroke the

force counteracting the working piston *a* remains approximately constant, especially if the receptacles *e* and *h* are relatively large. The valve *m* is automatically closed after 5 a short time and the piston is moved to the left only by the pressure p_0 in the receptacle *e*, during the return stroke the compressor piston *b* sucks new air for the charge through the pipe *n*. During this time the ignited combustible mixture at the left side 10 of the working piston *a* is discharged more and more through the nozzle *o*. During this whole period the ignited combustible mixture has a pressure which is only a little 15 smaller than the specific pressure p_0 , and therefore nearly constant. After the piston is sufficiently moved to the left, new mixture is admitted to the combustion chamber *a* and ignited, and a new cycle of working 20 begins. The air escaping from the large receptacle during one cycle in consequence of leakage may be replaced by compressed air, which is pressed at a suitable moment by the compressor piston *b* in the receptacle 25 *e* through the controlled channel *r*. The pipe *d* may also be controlled by means of a valve so that the right side of the working piston *a* is connected to the receptacle *e* only during the first part of the forward 30 stroke (to the right), and is gradually disconnected therefrom, and even may be connected to the atmosphere by means of a secondary pipe *d'*, which can be closed by a valve *y*, while the counter-pressure at the 35 right side of the compressor piston *b* increases. The receptacles *e* and *h* may be connected to a single receptacle as shown in Fig. 2.

Instead of air, water or any other fluid 40 may act on the right side of the working piston *a*, the action of the mass of which, being larger than that of air, can be used in a suitable manner.

In order to neutralize the action of the 45 mass of the reciprocating parts, the piston engine may be made as a twin-cylinder engine as shown in Fig. 2. In this construction there are arranged two pistons *t* and *u* working in opposite directions in the working cylinder *s*, and to each of them there 50 is rigidly connected a compressor piston, *v* and *w*.

Instead of a single piston engine there 55 may be used several machines in parallel and arranged in a suitable manner with regard to the gasturbine proper. The gasturbine may be a single-stage or a multistage turbine, an action turbine or a reaction turbine, or it may be provided with impulse 60 wheels as well as with reaction wheels. The closing devices necessary in the different channels may be controlled in the known manner either automatically by the machine or by a speed governor.

65 The air or the fuel may be compressed in

a known manner, before they enter the compressor cylinder *b* (Fig. 1), for example by means of a centrifugal compressor.

I claim:

1. In an explosion gas turbine, the combination with a piston compressor, of a two cycle gas engine for impelling said compressor, the combustion gases of said engine expanding during the outward movement of its piston, an explosion chamber in continuous communication with the cylinder of said engine, nozzles connected to the combustion chamber, a rotor wheel, auxiliary means for expelling said combustion gases during the inward stroke of the piston of the gas engine at an approximately constant pressure and for causing these gases to flow during the whole working process through said nozzles at a speed of the greatest possible uniformity to said rotor wheel. 85

2. In an explosion gas turbine, the combination with a piston compressor, of a two cycle gas engine impelling said compressor, the combustion gases of said engine expanding during the outward movement of its piston, an explosion chamber in continuous communication with the cylinder of said engine, nozzles connected to the combustion chamber, a rotor wheel, auxiliary means for expelling said combustion gases during the inward stroke of the piston of the gas engine at an approximately constant pressure and for causing these gases to flow during the whole working process through said nozzles at a speed of the greatest possible uniformity to said rotor wheel, and a medium contained in said means connected during the greater part of a working process to the side of the gas engine cylinder opposite to that of the explosion chamber, said medium receiving work from the products of combustion during the outward stroke of the piston of the gas engine, while it transmits its work to said products during the inward stroke of said piston. 105

3. In an explosion gas turbine, the combination with a piston compressor, of a two cycle gas engine impelling said compressor, the combustion of said engine expanding during the outward movement of its piston, an explosion chamber in continuous communication with the cylinder of said engine, nozzles connected to the combustion chamber, a rotor wheel, auxiliary means for impelling said combustion gases during the inward stroke of the piston of the gas engine at an approximately constant pressure and for causing these gases to flow during the whole working process through said nozzles at a speed of the greatest possible uniformity to said rotor wheel, said means including a receptacle filled with air and connected during the greater part of a working process to the side of the gas engine cylinder opposite to that of the explosion chamber. 125

ber, the air in said receptacle receiving work from the products of combustion during the outward stroke of the piston of the gas engine, while the air transmits work to said products during the inward stroke of said piston.

4. In an explosion gas turbine, the combination with a piston compressor, of a two cycle gas engine impelling said compressor, 10 the combustion gases of said engine expanding during the outward movement of its position, an explosion chamber in continuous communication with the cylinder of said engine, nozzles connected to the combustion chamber, a rotor wheel, auxiliary means for impelling said combustion gases during the inward stroke of the piston of the gas engine at an approximately constant pressure and for causing these gases 15 to flow during the whole working process through said nozzles at a speed of the greatest possible uniformity to said rotor wheel, said means including a receptacle filled with air used for the combustion and connected 20 during the greater part of a working process to the side of the gas engine cylinder opposite to that of the explosion chamber, the air in said receptacle receiving work 25 from the products of combustion during the

outward stroke of the piston of the gas engine, while the air transmits work to said products during the inward stroke of said piston.

5. In an explosion gas turbine, the combination with a piston compressor, of a two- 30 cycle twin-cylinder gas engine having pistons working in opposite directions and im- 35 pelling said compressor, the combustion gases of said engine expanding during the outward movement of its pistons, an ex- 40 plosion chamber in continuous communica- 45 tion with the cylinder of said engine, noz- 50 zles connected to the combustion chambers, a rotor wheel and auxiliary means for ex- pelling said combustion gases during the inward stroke of the pistons of the gas engine at an approximate constant pressure and for causing these gases to flow during the whole working process through said noz- 55 zles at a speed of the greatest possible uni- formity to said rotor wheel.

In testimony that I claim the foregoing as my invention, I have signed my name in presence of two subscribing witnesses.

HEINRICH ZOELLY.
